MINIATURE POWER ACTUATED SINGLE PUNCH FOR IMPLANTING HAIR

Frank A. Bellantoni, 101 Helena Ave.,
Yonkers, N.Y. 10710

Filed Apr. 6, 1970, Ser. No. 22,248

Term of patent 14 years

Int. Cl. D24—03; D8—02
U.S. Cl. D83—12

Fig. 1.

Fig. 2.

Fig. 4.

Fig. 5.

FIG. 1 is a perspective view of the miniature power actuated single punch for implanting hair embodying the features of my new design;

FIG. 2 is a top plan view thereof;

FIG. 3 is a side elevational view thereof; and

FIG. 4 is a rear elevational view thereof.

I claim:

The ornamental design for a miniature power actuated single punch for implanting hair, substantially as shown.
